UNITED STATES PATENT OFFICE

GEORGE J. DISCHERT, OF PHILADELPHIA, PENNSYLVANIA

SLICING APPARATUS

Application filed May 26, 1928. Serial No. 280,717.

This invention relates to apparatus useful in slicing articles in loaf form, more particularly bakery products such as bread or cake.

The main object of my invention is to enable rapid and uniform slicing of articles like the aforementioned under absolutely sanitary conditions and with minimum waste.

A further object of my invention is to attain the foregoing ends in an apparatus which is extremely simple in construction and operation, inexpensive to manufacture and capable of easy regulation so that the thickness of the slices may be varied as desired or required.

Still further objects and attendant advantages of my invention will be manifest from the detailed description which follows of the typical embodiment of this invention illustrated in the drawings.

Fig. I is a perspective view of my improved slicing apparatus.

Fig. II shows a longitudinal section of the apparatus, taken as indicated by the arrows II-II in Figs. I and V.

Fig. III is a transverse sectional view, taken as indicated by the arrows III-III in Fig. II.

Fig. IV is a detail section, viewed in the direction of the arrows IV-IV in Fig. I.

Fig. V is a cross sectional view, taken as indicated by the arrows V-V in Fig. II; and,

Fig. VI is a detail sectional view, taken as indicated by the arrows VI-VI in Fig. IV.

As herein delineated the slicing apparatus comprises a box 10 which is substantially rectangular in configuration and preferably constructed throughout from sheet metal. A transverse partition 11 sets apart a comparatively narrow interspace 12, behind the removable frontal wall 13 of the box 10; while a compartment 14 is defined by longitudinal partitioning 15, 16 to accommodate the loaf L which is to be sliced. The compartment 14 is accessible from the top of the box 10, through an opening protected by a hinged closure lid 16', see Figs.

I, II and V. The remaining space in the box 10 is subdivided by a shelf 17 with creation of further compartments 18, 19 which may be employed as storage compartments for extra loaves L'; said subdivisions 18, 19 being accessible through a laterally swinging door 20 at one side of the box 10. From Figs. II-IV it will be observed that the partition 11 has an arched opening 21, in line with the compartment 14, for projection of the forward end of the loaf L into the path of a rotating blade 22 located in the interspace 12, said blade having a curved cutting edge 22^a, adapted to sweep across the opening 21 aforesaid, to sever slices from the loaf L as well as a trailing portion 22^b, and an angular recession at 22^c functional in a manner hereinafter explained. As shown in Figs. IV and VI the cutting blade 22 is securely clamped, by means of a nut 23, against a circumferential flange disk 24 of a tubular shaft 25 which is mounted, for free rotation, on a stud axis 26 suitably anchored in the partition 11, and extends outward through an opening in the frontal wall 13 of the box 10. A collar 27, at the outer end of the stud axis 26, restrains the tubular shaft 25 against displacement with the cutting blade 22 bearing on an annular bead 11^a, offset laterally from the partition 11, see Figs. II, III and IV. Keyed to the tubular shaft 25, with capacity to slide longitudinally thereon for a purpose later explained, is a sleeve 28 which, at its inner end, carries a segmental cam 29 with angularly deflected terminal wings 29^a, 29^b. Externally of the box 10 the sleeve 28 has secured to it a driving means having, in the present instance, the form of a crank handle 30 for manual operation. However, if power operation of the device is desired, a pulley or a gear may obviously be substituted for the crank handle 30.

The loaf L is urged forward in the compartment 14 by a follower 32 which may be conveniently fashioned from sheet metal with a vertical buttress portion 33, and a laterally turned end portion 34 providing ears 35 to engage guide rods 36, fixedly secured along one side of the compartment 100.

14. The turned end portion 34 of the follower 32 carries a pin 37 which projects into the hollow side wall 38 of the box 10 (Fig. V) for engagement by a lever 39. This lever 39 is fulcrumed at its lower end on a screw 40, and is acted upon by a helical tension spring 41. To facilitate its retraction in opposition to the action of the spring 41 while inserting a new loaf L into the compartment 14, the follower 32 is equipped with a hand grasp 42.

The extent of forward projection of the loaf L under urge of the follower 32 beyond the plane of the cutting blade 22 is limited by a stop plate 45 which is thus instrumental in determining the thickness of the slices. This stop plate 45 is hinged, along its upper edge at 46, within the top of the frontal interspace 12 of the box 10, and is subject to a leaf spring 47 which tends to push it forward toward the wall 13. During cutting of the bread slices by the blade 22, the stop plate 45 is held in the position shown in the drawings by the segmental cam 29 which over-travels it. As shown in Fig. III the stop plate 45 has angularly deflected tabs 45^a, 45^b which lie in the path of the wings 29^a, 29^b, of the segmental cam 29. By virtue of this provision, the stop plate 45 is moved inward to the normal or active position without attendant abruptness or noise, and its recession to free the cut bread slices is similarly eased with avoidance of slamming against the frontal wall 13 of the box 10 under the push of the leaf spring 47.

To prevent flexure of the cutting blade 22 during the slicing operation under pressure of the loaf L, I place a cross bar 50 within the interspace 12 which affords outer surface bearing for said blade. The cross bar 50 also functions as a support for a chute 51 by which the cut slices are directed to a discharge opening 52, in the frontal wall 13 of the box 10. To receive the bread slices so discharged the box 10 is equipped with a drawer or tray 53 which is slideable in a guideway formed in the hollow bottom 54 of said box in line with the discharge opening 52. An auxiliary chute 55 within the frontal interspace 12 serves to direct crumbs from the region of the cutting into the rear end of the drawer 53 when the latter is withdrawn from the box 10 to receive the severed bread slices.

In operation of the apparatus, as the handle 30 is turned clockwise, or in the direction of the arrow in Fig. I, that portion of the loaf L, projecting forward of the plane 60 of the cutting blade 22 is severed incidental to sweep of the latter past the opening 21 of the partition 11, the extent of the loaf projection and the thickness of the slice being determined as previously stated, by the stop plate 45. Immediately after the cut-

ting of the slice as just explained, the stop plate 45 is released to the action of its spring 47 as a consequence of the circular advance of the segmental cam 29 from engagement therewith, the slice being thus freed to drop, under the guidance of the chute 51, through the discharge opening 52 into the drawer or tray 53, previously withdrawn to receive it. During the discharge of the slice, the bread loaf L is restrained from moving through the opening 21, of the partition 11, by the trailing portion 22^b of the knife blade 22, until the angular recession 22^c of said blade registers with the opening 21 to permit forward movement of the bread loaf L under urge of the follower 32, as already understood.

In order that the thickness of the slices may be varied, the apparatus is equipped with means for adjusting the position of the segmental cam 29, on the tubular shaft 25 of the cutting blade 22, to alter the normal or active position of the stop plate 45, relative to the partition 11. This adjusting means is detailed in Figs. IV and VI, wherefrom it will be noted the same embodies a thumb nut 56 which engages the diametrically reduced threaded end 25^a of the cutting blade tubular shaft 25, and bears against the outer end of the sleeve 28 thereby opposing a helical spring 57, in compression between the inner end of said sleeve and the clamp nut 23. Thus by turning the thumb nut 56 in one direction, the segmental cam 29 is moved inward, while, by turning it in the opposite direction said cam is moved outward by the spring 57 with corresponding changes in the normal or active position of the stop plate 45. Notwithstanding adjustment of the cam 29, in the manner just explained, the outward swing of the stop plate 45 to free the cut slices is always limited as a consequence of abutment with the frontal wall 13 of the box 10.

From the foregoing it will be seen that I have provided a slicing apparatus which is simple and compact in construction, absolutely sanitary and by aid of which articles in loaf form can be rapidly cut into subdivisions of uniform thickness without waste or deformation.

Having thus described my invention, I claim:

1. In apparatus for slicing bread loaves or the like, means for guiding the loaf, cutting means movable crosswise of the loaf, means to urge the loaf toward the cutting means, and stop means under control of a rotary winged cam to limit the projection of the loaf end beyond the plane of the cutting means, thereby to determine the thickness of the slices, said stop means having tabs co-active with the cam wings during each actuation of the cutting means to effect retraction of the stop means for freeing the

severed slices and to return the same to active position.

2. In apparatus for slicing bread loaves and the like, means for guiding the loaf, 5 rotary cutting means movable crosswise of the loaf, means to urge the loaf toward the cutting means, stop means under control of a segmental winged cam to limit projection of the loaf end beyond the plane of the cutting means thereby to determine the thickness of the slices, said stop means having deflected tabs co-active with the cam wings during each rotation of the cutting means to effect retraction of the stop means to release the severed slice and subsequently return the same to normal active position, and means whereby the stop means can be adjusted to regulate the slice thickness. 10

3. In apparatus for slicing bread loaves 20 and the like, guide means for the loaf, rotary cutting means movable crosswise of the loaf, means to urge the loaf toward the cutting means, stop means to limit projection of the loaf end beyond the plane of the cutting means thereby to determine the thickness of the slices, a rotary winged cam movable with the cutting means to hold the stop means in fixed position during each cutting operation, and means for subsequently re- 25

30 tracting the stop means to free the slice.

4. In apparatus for slicing bread loaves or the like, means to guide the loaf, cutting means movable crosswise of the loaf, means to urge the loaf towards the cutting means, 35 a stop plate to limit projection of the loaf end beyond the plane of the cutting means, thereby to determine the thicknesses of the slices, a cam movable with the cutting means adapted to overtravel the stop plate and hold it positionally fixed during each cutting 40 operation, and means operative upon passage of the cam for retracting the stop to free the slice.

5. In apparatus for slicing bread loaves 45 and the like, means for guiding the loaf, a rotary cutting blade movable crosswise of the loaf, means to urge the loaf toward the cutting blade, a stop plate to limit projection of the loaf end beyond the plane of the cutting blade thereby to determine the thickness of the slices, a segmental cam mounted on the axis and rotatable with the cutting blade for capacity to over-travel the stop plate and hold it positionally fixed 50 during each cutting operation, said cam being axially adjustable on the blade axis for regulation of the slice thickness, and means operative upon passage of the cam for re-tracting the stop plate to free the slice. 55

6. In apparatus for slicing bread loaves and the like, means for guiding the loaf, a rotary cutting blade movable crosswise of the loaf, means to urge the loaf toward the cutting blade, a stop plate to limit projection of the loaf end beyond the plane of 60

the cutting blade thereby to determine the thickness of the slices, a segmental cam mounted on the blade axis and rotatable with the blade for capacity to over-travel the stop plate and hold it positionally fixed 70 during each cutting operation, said cam being axially adjustable on the blade axis for regulation of the slice thickness, and means operative upon passage of the cam for re-tracting the stop plate to free the slice. 75

7. In apparatus for slicing bread loaves and the like, means for guiding the loaf, a rotary cutting blade movable crosswise of the loaf, means to urge the loaf toward the cutting blade, a stop plate to limit projection of the loaf end beyond the plane of the cutting blade thereby to determine the thickness of the slices, a segmental cam mounted on the blade axis and movable with the blade for capacity to over-travel the stop plate and hold it positionally fixed during each cutting operation, means on the blade axis for adjusting the cam to predetermine the normal position of the stop plate relative to the cutting blade and thereby regulate the slice thickness, and means operative upon passage of the cam for retracting the stop plate to free the slice. 80

8. In apparatus for slicing bread loaves or the like, means for guiding the loaf, cutting means movable crosswise of the loaf, means to urge the loaf toward the cutting means, stop means under control of an adjustable rotary cam to limit projection of the loaf end beyond the plane of the cutting means thereby to determine the thickness of the slices, and means to restrain the loaf incidentally to release of the stop means for the purpose of freeing the cut slices. 90

9. In apparatus for slicing bread loaves or the like, means for guiding the loaf, cutting means movable crosswise of the loaf, means to urge the loaf toward the cutting means, and stop means under control of a rotary adjustable winged-cam to limit projection of the loaf end beyond the plane of the cutting means thereby to determine the thickness of the slices, the cutting means aforesaid having a trailing portion functional in restraining the loaf incidental to 100 release of the stop means for the purpose of freeing the cut slices. 110

10. In apparatus for slicing bread loaves and the like, means for guiding the loaf, a rotary cutting blade movable crosswise of the loaf, means to urge the loaf toward the cutting means, and stop means under control of an adjustable winged-cam rotating with the cutting blade to limit projection of the loaf end beyond the plane of said cutting blade to determine the thickness of the slices, said cutting blade having a trailing portion functional in restraining the loaf incidental to release of the stop means for the purpose of freeing the cut slices. 120 125 130

11. In apparatus for slicing bread loaves and the like, a box affording a compartment to accommodate and guide the loaf, said box having a transverse partition to set apart a narrow interspace behind its frontal wall, a cutting blade with exterior actuating means movable crosswise of an opening in the partition, means for urging the loaf forward in the compartment through the partition opening, a stop under control of an adjustable winged-cam rotating with the cutting blade to limit the projection of the loaf end beyond the cutting blade, thereby to determine the thickness of the slices, said stop retracting automatically with each actuation of the knife to free the severed slice, and a chute also within the interspace aforesaid to guide the slices to a discharge opening in the frontal wall of the box.

12. In apparatus for slicing bread loaves and the like, a box affording a compartment to accommodate and guide a loaf, said box having a transverse partition to set apart a narrow interspace behind its frontal wall, a cutting blade, with exterior actuating means movable in such interspace crosswise of an opening in the partition, means for urging the loaf forward in the compartment through the partition opening, stop means within the interspace to limit projection of the loaf beyond the plane of the cutting blade to determine the thickness of the slices, said stop means retracting automatically with each actuation of the blade to free the severed slice, a chute within the interspace aforesaid to guide the slices to a discharge opening in the frontal wall of the box, a sliding tray beneath the discharge opening for receiving the slices, and an auxiliary chute also within the interspace for conducting crumbs from the region of cutting into the rear of the sliding tray.

13. In apparatus for slicing bread loaves and the like, a box affording a compartment to accommodate and guide a loaf, said box having a transverse partition to set apart a narrow interspace behind its frontal wall, rotary cutting blade movable in such interspace crosswise of an opening in the partition, the shaft of said rotary blade extending through the frontal wall of the box for attachment of drive means, means for urging the loaf forward through the partition opening, and stop means under control of an adjustable winged-cam rotating with the cutting blade to limit projection of the loaf beyond the cutting blade to determine the thickness of the slices, said stop means retracting automatically with each actuation of the blade to free the slice for discharge through an opening in the frontal wall of the box.

14. In apparatus for slicing bread loaves and the like, a box affording a compartment to accommodate and guide a loaf, said box

having a transverse partition to set apart a narrow interspace behind its frontal wall, a rotary cutting blade movable in such interspace crosswise of an opening in the partition, the shaft of said rotary blade extending through the frontal wall of the box for attachment of drive means, means for urging the loaf forward through the partition opening, stop means under control of a segmental-cam having angularly deflected wings and rotating with the cutting blade to limit projection of the loaf beyond the cutting blade to determine the thickness of the slices, said stop means retracting automatically with each actuation of the blade to free the slice for discharge through an opening in the frontal wall of the box, and adjusting means accessible at the exterior of the box for regulating the normal position of the stop means to vary the slice thickness.

15. In apparatus for slicing bread loaves and the like, a box affording a compartment to accommodate and guide a loaf, said box having a transverse partition to set apart a narrow interspace behind its frontal wall, a rotary cutting blade movable in such interspace crosswise of an opening in the partition, the shaft of said rotary blade extending through the frontal wall of the box for attachment of drive means, means for urging the loaf forward through the partition opening, stop means under control of a segmental-cam having angularly deflected wings and rotating with the cutting blade to limit projection of the loaf beyond the cutting blade to determine the thickness of the slices, said stop means retracting automatically with each actuation of the blade to free the slice for discharge through an opening in the frontal wall of the box, and adjusting means manipulatable at the posterior end of the cutting blade shaft for regulating the normal position of the stop to vary the slice thickness.

In testimony whereof, I have hereunto signed my name at Philadelphia, Pennsylvania, this 22nd day of May, 1928.

GEORGE J. DISCHERT.
